(57) CLAIM

The ornamental design for pants, as shown and described.

DESCRIPTION

FIG. 1 is a front perspective view of pants showing my new design in a first embodiment;

FIG. 2 is a front view thereof;

FIG. 3 is a back view thereof;

FIG. 4 is an enlarged view of the detail shown on the right front pocket of FIG. 2;

FIG. 5 is a right side view of the pants shown in FIG. 1;

FIG. 6 is a left side view thereof;

FIG. 7 is a front perspective view of the pants showing my new design in a second embodiment;

FIG. 8 is a front view thereof;

FIG. 9 is a back view thereof;

FIG. 10 is an enlarged view of the detail shown on the right front pocket of FIG. 8;

FIG. 11 is a right side view of the pants shown in FIG. 7; and,

FIG. 12 is a left side view thereof.

The evenly spaced broken lines in the drawings depict portions of the pants. The long-dash short-dash broken lines depict enlargements. The broken lines form no part of the claimed design.

The pants in FIGS. 7, 8, 10 and 11 are shown with a symbolic break in their length. The appearance of any portion of the article between the break lines forms no part of the claimed design.
